U.S. Cl. D34—15

FIG. 1

FIG. 2

Des. 220,576

PAGE 2

FIG. 3

FIG. 4

FIG. 5

FIG. 6

FIG. 1 is a perspective view of the toy airplane, embodying my new design;

FIG. 2 is a plan view thereof;

FIG. 3 is a side elevational view thereof;

FIG. 4 is a front elevational view thereof;

FIG. 5 is a rear elevational view thereof; and

FIG. 6 is a bottom view thereof.

I claim:

The ornamental design for a toy airplane, as shown.
